WINDOW OPERATING MECHANISM

Richard W. Treverton, Buffalo, N. Y., assignor
to Trico Products Corporation, Buffalo, N. Y.

Application October 15, 1941, Serial No. 415,103

3 Claims. (Cl. 268—125)

The present invention relates to operating mechanisms for windows and has particular relation to fluid pressure operated devices, such as are adapted for use on automobiles and other vehicles, and to means for controlling such devices.

For operating windows it has been known to employ a cylinder having a piston movable therein by differential fluid pressures, such as the less-than-atmospheric pressure maintaining in the intake manifold of a gasoline engine and atmospheric pressure. Manually operable valve means have been provided to apply the pressures to the cylinder for opening or closing the window, but since the motion is fairly rapid and the pressure difference may persist for a time after the valve means are closed, some difficulty or experimentation may be required by a person unfamiliar with the operation, in obtaining the particular window adjustment that is desired.

The present invention contemplates means whereby the window adjustment may be preselected, by the positioning of a control handle of the valve means, and whereby the operating means will stop the window automatically when it reaches this preselected position.

These and other objects and advantages will become apparent from the following description of the typical embodiment of the invention shown in the accompanying drawing, wherein:

Fig. 1 is a side elevation of the window and operating mechanism therefor;

Fig. 2 is a central vertical sectional view through the control valve means;

Fig. 3 is a plan sectional view through the control valve means, taken approximately on line 3—3 of Fig. 2; and,

Fig. 4 is a fragmentary elevational view of one of the valve members.

As shown in the drawing the window 11 may be supported in suitable guides (not shown) for vertical movement to open or close a window opening 12 in a vehicle or other structure 13. A carrier bar 14 supporting the window, and extending along the lower edge thereof, has a channel 15 receiving a roller 16. The latter is carried by an arm 17 of a bell crank lever pivoted at 18 to the structure 13, the other arm 19 of the lever being pivoted to one end of a piston rod 21. A piston on the other end of the rod is slidable in a cylinder 22 which is pivoted at 23 to a part 24 of the structure 13.

Communicating with the opposite ends of the cylinder 22 are conduits 25 and 26 which are connectible by valve means either to the atmosphere

or to a source of operating pressure, such as the intake manifold of an internal combustion engine, where the pressure is usually less-than-atmospheric. By applying atmospheric pressure through conduit 26 and suction or less-than-atmospheric pressure through the conduit 25 when the window is lowered, the piston and rod 21 will be moved to the right to the position shown in Fig. 1, swinging the crank counter-clockwise about its pivot 18 and raising the window 12 to the position shown, the roller 16 moving along the guide channel 15 during this action. Reversal of the pressures i. e. application of suction through conduit 26 and atmospheric pressure through conduit 25 will effect lowering or opening movement of the window.

The conduits 25 and 26, which are preferably of rubber or other flexible material, terminate in nipples 27 and 28, respectively, which open into ports 29 and 31 formed in the valve seat 32 of a valve casing. The latter consists of casing members 33 and 34 secured together by fasteners 35 and mounted by fasteners 36 upon the structure 13. This structure, when constituting the door or body panel of a motor vehicle, may have upholstering 37 thereon.

Slidable on the seat 32 and within the valve casing 33, 34 is a valve member 38 having ports 39 and 41 which register, respectively, with the ports 29 and 31 and are spaced by a partition 42. As shown in Figs. 3 and 4 the valve member 38 also has a port 43 spaced laterally from the ports 39 and 41 and registering with a port 44 in casing member 33. Port 44 opens into a conduit 45 extending to a suitable source of suction or less-than-atmospheric pressure. An extension 46 from the valve member 38 is pivoted to a link 47 which is also pivoted at 48 to arm 17 of the bell crank.

Within the valve casing and slidable upon the valve 38 is a valve member 51 which normally closes both ports 39 and 41 and has a recess 52 (the T-shaped recess shown in broken lines in Fig. 4) normally overlying the partition 42 and registering with the port 43 when ports 38 and 51 are in any position.

The valve casing has a bearing sleeve portion 54 extending through the structure 13 and upholstering 37; and journaled in this bearing is a shaft 55 having fixed to its outer end a handle 56 and to its inner end a crank 57 which has a crank pin 58 received in a transverse groove 59 in the rear face of valve member 51.

In operation, when the handle is moved downwardly from the full up position, shown in Fig.

1, wherein the window will normally be closed, the valve member 51 will be lowered relative to valve member 38 as well as absolutely, so port 39 will be opened to the atmosphere (the casing 33, 34 is not airtight) and port 41 will be placed in communication with recess 52. Accordingly atmospheric air will enter the right end of the cylinder 22 via port 39, port 29, nipple 27 and conduit 25 while air will be exhausted from the left end of the cylinder via conduit 26, nipple 28, port 31, port 41, recess 52, port 43, port 44 and through nipple 45 to the source of suction.

In response the piston and rod 21 will be moved to the left, swinging lever 19, 17 clockwise and lowering the window. As the lever swings to close the window, the rod 47 will be lowered causing the valve slide 38 to lower. When the window reaches the closed position, which is the position selected by movement of the handle 56, the member 38 will have reached a position relative to valve member 51 like that shown in Fig. 2, i. e. port 39 will be closed against the entrance of atmospheric air and recess 52 will be closed from the port 41, thereby automatically stopping application of the differential pressures with the result that movement of the window will also stop. If due to momentum or other cause the window should move appreciably beyond the selected position, the valve 38, 51 will automatically be reversed, opening port 41 to the atmosphere and registering port 39 with recess 52, which will apply atmosphere and suction respectively to the left and right ends of the piston, correcting the overtravel of the window.

Similarly when the control handle is moved upwardly to any selected position, the valve parts 38 and 51 will so move as to apply differential pressures to the cylinder to effect raising of the window to the selected position, and, when the window reaches the selected position, cut off the application of differential pressure to stop the window in that position.

It will be seen that the valve, which happens to be a slide valve in the illustrated embodiment although any other suitable types of valve might be employed, is actuated by relative movement of link 47 which moves in accordance with movement of the window, and member 51 which moves in accordance with handle 56. It will be also understood that the inventive principles incorporated in the structure specifically shown and described herein may be otherwise embodied without departing from the spirit of the invention or the scope of the appended claims.

What is claimed is:

1. In a window and operating mechanism therefor, a fluid pressure operated actuating device and a vertically slidable window movable thereby to and from an elevated closed position through a bell crank transmission, a valve for controlling application of a fluid pressure dif-

ferential to said device for causing movement of the window between opened and closed positions, said valve comprising a manually operable member movable to any of a plurality of positions to apply said fluid pressure differential to the device, and a member operatively connected to the bell crank adjacent its pivotal mounting and movable in accordance with movement of the window for cutting off the application of the pressure differential when the window reaches a position corresponding to the position of said manually operable member.

2. In a window and operating mechanism therefor, a fluid pressure operated actuating device, a window, a bell crank pivotally mounted and operatively connecting the actuating device to the window for moving the latter, valve means therefor comprising a manually operated member adapted to be pre-set to correspond to the desired position of the window, and a member movable in accordance with movement of the window, a link connecting the latter member to the bell crank adjacent its pivotal mounting, said members cooperating to enable application of fluid pressure to the actuating device to move the window to the position predetermined by the setting of the manually operated member and to cut off the application of pressure when the window reaches said predetermined position.

3. In a window operating mechanism, a fluid pressure operated device comprising a chambered element having a relatively movable wall element therein, one of said elements being connected to the window for moving the same, a valve member having a pair of ports therein spaced by a partition and each communicating with the chamber on one of the opposite sides of said wall, said valve member being connected to the window for movement in accordance with movement of the window, a second valve member overlying the first and having a recess connectible to a source of operating pressure, said second valve member being manually movable and being adapted to substantially close said ports when the recess thereof is in registry with said partition and to uncover one of said ports to a pressure different from that of said source when the recess thereof is in registry with the other of said ports, the fluid operated device being subjected to differential pressures tending to move the window to a position corresponding to that of said second valve member and such pressure differential being cut off when the window reaches such position, the arrangement being such that should the window actuated valve member override the position determined by the second valve member it will uncover one of said ports to effect a restoration of the window to such predetermined position.
